UNITED STATES PATENT OFFICE.

ANTOINE FRANCE, OF LIEGE, BELGIUM.

PLANT FOR WASHING COAL AND OTHER MINERALS BY MEANS OF LIQUID STREAMS.

Application filed February 26, 1924. Serial No. 695,262.

To all whom it may concern:

Be it known that I, ANTOINE FRANCE, a subject of the King of the Belgians, residing at Liege, Belgium, 17 Quai Saint 5 Leonard, have invented new and useful Improvements in or Relating to Plants for Washing Coal and Other Minerals by Means of Liquid Streams, of which the following is a specification.

10 The present invention relates to improvements in plant for washing coal and other minerals by means of liquid streams, and more particularly to plant of the kind wherein two or more wet sorting apparatus 15 crossed by adjustable upward streams are arranged at intervals along a sloping launder in which the products are first classified under the influence of a so-called "horizontal" liquid stream, and to which suitable mechanical means (such as for instance a bucket elevator) return, substantially at the point 20 where the raw products are fed to the said launder, the products discharged by the last one or ones of the wet sorting apparatus 25 pending from the aforesaid launder. The wet sorting apparatus referred to may for instance be of the type described and claimed in the specification of Patent No. 1,492,025 granted February 25th 1924, and in the specification of Patent No. 1,441,571 granted 30 January 9th 1923.

The characterizing principle of the present invention essentially resides in the provision, in mineral washing plants of the 35 kind referred to, of a complementary or additional wet sorting apparatus depending from an extension of the launder at a point situated up-stream in relation to the point of introduction of the raw products into the 40 said launder, together with suitable mechanical means (such as for instance a bucket elevator) for bringing back to the top end of such launder extension the products discharged by the first one or ones of the wet 45 sorting apparatus situated down-stream in relation to the point of introduction of the raw products into the launder, a crushing mill being placed in the launder extension immediately downstream in relation to the 50 additional wet sorting apparatus for the purpose of disintegrating the so-called "striped" particles (i. e. wherein constituents of different specific gravities are closely allied in individual particles) which may be 55 contained in the raw mineral.

In order that the nature and the mode of operation of the invention may be more readily understood, the said invention will now be described in detail by reference to the accompanying illustrative drawings, 60 wherein:

Fig. 1 is a diagrammatic longitudinal elevation, partly in section, of an embodiment of a mineral washing plant carried out in accordance with the invention, and more particularly designed for the treatment of coal containing a proportion of "striped" particles, that is to say particles which are not of uniform composition throughout their mass and wherein constituents of different 65 specific gravities are closely allied in an individual particle, and

Figs. 2 to 7 are transverse sections through the launder taken respectively at the points 2-2, 3-3, 4-4, 5-5, 6-6 and 7-7, of 70 Fig. 1.

In the various sectional views through the launder, Figs. 2 to 7, the layers constituted by the various categories of products and the liquid stream are represented in the following conventional manner:

The diagonal cross shading indicates pure "schists" or products of high specific gravity;

The plain vertical shading indicates intermediate or regulating products;

The dotted shading indicates pure coal or products of low specific gravity;

The plain horizontal shading indicates "striped" particles, and the broken line 90 horizontal shading indicates water.

Referring to Fig. 1, the plant comprises a launder *a*, slightly sloping in relation to the horizontal, and in which the raw products to be treated are fed by means of a supply 95 hopper *b*, in order to be classified in the said launder under the influence of a so-called "horizontal" water stream. This launder is, according to the present invention, extended up-stream in relation to the point of 100 introduction of the raw products, as indicated at *a'*. At intervals along the launder proper *a* are arranged wet sorting apparatus, of which two, *c* and *d* respectively, are provided in the present instance.

These wet sorting apparatus are partitioned by a perforated sloping screen *e* so as to constitute in their upper portion a sorting chamber in communication with the launder and in which the products tending 110

to sink therein are subjected to the action of an upward water stream. The water for the so-called "horizontal" stream in the launder and the upward streams in the wet sorting apparatus is supplied by means of branch-pipes f' on a main supply-pipe f supplying water under pressure, the said streams being adjustable by means of valves g or the like provided on the branch-pipes f' . The discharge of the products to be withdrawn by the wet sorting apparatus is effected by means of foraminous sector shaped oscillatory flaps h , suitably operated and forming a movable bottom for the sorting chamber of the said apparatus. Means of particular construction, comprising substantially a vertical plate or wall i having its upper portion bent back against the bottom of the launder, and movable in a horizontal direction by means of a suitable adjustment device j operated from outside, are provided in the embodiment illustrated for adjusting the size of the sorting chamber of each apparatus and of the passage for the discharged products resulting from the opening of the oscillatory flaps h .

A bucket elevator k is provided to take up the discharged products from the last one d of the wet sorting apparatus depending from the launder a and to return same by way of a chute l to the top of the launder a close to the point of introduction into the latter of the raw products which are fed thereto by the supply hopper b .

35 A complementary or additional wet sorting apparatus m , of construction identical to that of the apparatus c and d is according to the present invention arranged on the extended portion a' of the launder up-stream, 40 in relation to the supply of raw products, and a bucket elevator n is provided to take up and to return, by way of a chute o , to the top end of the said extension a' of the launder, and therefore up-stream in relation 45 not only to the point of supply of the raw products but also to the complementary wet sorting apparatus m , the products discharged by the first one c of the wet sorting apparatus situated down-stream in relation 50 to the point of introduction into the launder of the raw products fed thereto by the supply hopper b . Finally a bucket elevator q is provided to effect the removal of the products discharged by the complementary 55 wet sorting apparatus m .

The plant according to the invention, moreover comprises a suitably operated crushing mill r or like device, arranged in the extended portion a' of the launder between the complementary wet sorting apparatus m and the point of introduction into the said launder of the raw products fed thereto by the supply hopper b .

The operation of the plant shown in Fig. 1 may briefly be described as follows:

The raw products are fed by the supply hopper b to the launder a in which they are taken up and sorted by the so-called "horizontal" water stream, so that just before the sorting apparatus c (section Fig. 5) the 70 products are divided into three layers: a layer of "schists" or high specific gravity material on the bottom of the launder, a layer of products of intermediate specific gravity and "striped" particles above this 75 layer of "schists", and finally uppermost a layer of clean coal. There may readily be withdrawn by this sorting apparatus c a quantity of material comprising the totality 80 of the pure schists or products of high specific gravity and a portion of the intermediate products and "striped" particles, so that immediately before the second wet sorting apparatus d (which constitutes what 85 may be called a regulating-product apparatus) the cross section of the launder has the appearance shown in Fig. 6, that is to say with the pure schists entirely eliminated the remainder of the intermediate products and of the "striped" particles on the bottom of 90 the launder, and the clean coal above. At this point, there may be readily withdrawn by the wet sorting apparatus d the whole of the remainder of the intermediate products and of the "striped" particles and even a small portion of clean coal, so as to be absolutely certain to obtain at the lower end 95 of the launder a (section Fig. 7) absolutely clean coal only. The wet sorting apparatus d 100 may be called regulating product apparatus because it is the means of obtaining products serving a regulating purpose in this sense that the said products are brought back by the elevator k to a point of the launder a immediately down-stream in relation to the supply 105 of raw products; and, being constituted of particles of intermediate specific gravity and of "striped" particles of which the mean specific gravity assimilates them to the said intermediate particles, form a kind of partition between the extreme products, i. e. between the products of highest and of lowest 110 specific gravities, as shown in Fig. 5.

As to the products discharged by the apparatus c , these products, consisting of 115 "schists" or products of high specific gravity and of just such portion of intermediate products and "striped" particles which are of highest specific gravity, are introduced into the extended launder a' up-stream in relation to the supply of raw products and to the complementary wet sorting apparatus m , which is also situated up-stream in relation to the supply of raw products and constitutes what may be called a pure "schist" 120 apparatus. The material in the launder just before this complementary sorting apparatus m (section Fig. 2) shows two layers: pure "schists" on the bottom of the launder and striped particles and intermediate prod- 125 130

ucts of comparatively highest specific gravity above. It will be readily understood that the withdrawal of absolutely pure "schists" by this wet sorting apparatus *m* 5 may easily be obtained as there are only two layers of products in the launder at this point.

The launder extension *a'* immediately downstream in relation to the said wet sorting apparatus *m* thus contains practically nothing else than a layer of dense intermediate products together with "striped" particles (see section Fig. 3). The latter being disintegrated by the crushing mill *r* so 10 as to detach the "coal" constituent from the "schist" constituent allied thereto in the individual particles, such coal and such schist, take their place respectively above and below the intermediate products as 15 shown in section Fig. 4, and immediately downstream in relation to the supply of raw products from the hopper *b*, join respectively the coal and the schist contained in the raw product while the intermediate 20 products interpose themselves between the extreme layers of the raw products and thus increase the thickness of the artificial partition constituted by the initial intermediate products between the extreme products, 25 which ensures the discharge by the sorting apparatus *c* of a product entirely free of clean coal.

When this layer of intermediate products becomes too thick, the products in the said 30 layer which are of comparatively lower specific gravity, i. e. the cleanest, which form the top portion of the layer, are discharged together with the clean coal, while those of comparatively higher specific gravity, i. e. those of highest ash-contents, which 35 travel immediately above the layer of "schists", are discharged with the pure "schists", which constitutes an ideal separation. The plant illustrated possesses the advantage of considerably simplifying the 40 crushing device, as even in the case where "striped" particles should escape separation on their initial passage through the plant they will by the mere mode of operation 45 of the said plant be brought back to the said crushing device until the dissociation of the various constituents allied in the individual "striped" particles is completely effected.

50 The advantages of the mineral washing plant according to the invention may be summarized as follows:

1st. Increased efficiency of the apparatus 55 for the elimination of "schists" situated upstream in relation to the supply of raw products, resulting from the absence of products of low specific gravity in the portion of the launder extending upstream in relation to the said apparatus: Consequently, the efficiency of the washing process may be pushed

up to the extremely fine particles, whereby products ranging in size from 0 up to 3 inches may be treated at the same time.

2nd. Complete automaticity of the washing plant, obviating any variations in the 70 supply and the nature of the raw products in view of the great possibilities of compensation due to the three wet sorting apparatus;

3rd. Reduction of the initial cost of the 75 plant, the described arrangement being of an efficiency equal to that of two distinct complete installations with two wet sorting apparatus each;

4th. Reduction of the water consumption 80 owing to the fact that there is only a single launder, and consequent reduction of the size of the settling tanks, of the required output of the pumps, etc.

5th. Simplification of the crushing device 85 and consequent reduction of the cost of erection and up-keep in the case of the treatment of raw products containing a certain proportion of "striped" particles.

It should be expressly understood that the 90 invention is in no way restricted to the embodiments illustrated, and more particularly that the bucket elevators provided in the illustrated embodiments for returning to the launder the products discharged by some of the wet sorting apparatus may be replaced by any other mechanical means suitable for the purpose, for instance by pumps in cases where the raw products consist of particles 95 of small size only.

I claim:

1. In plant for washing coal and other minerals by means of liquid streams, the combination with a launder for the initial classification of the mineral under the influence of a liquid conveying stream having a slight downward slope in relation to the horizontal, means for feeding the raw mineral to the highest end of said launder, a plurality of adjustable wet sorting apparatus for completing the classification under the action of upward liquid streams, depending from and in communication with the launder, and mechanical means for removing the products discharged by the sorting apparatus closest to the low end of the launder and returning them into said launder immediately below the aforesaid feeding means, of: a launder extension leading 105 to the highest end of the aforesaid launder, an additional adjustable upward stream wet sorting apparatus depending from and in communication with said launder extension, mechanical means for removing the products 110 discharged by the sorting apparatus closest to the high end of the launder and discharging them into the portion of the launder extension leading to the additional sorting apparatus, and a crushing mill arranged in 115 the aforesaid launder extension between the 120

last named sorting apparatus and the high end of the launder, substantially as described.

2. In plant for washing coal and other minerals by means of liquid streams, the combination of: a launder having a slight downward slope in relation to the horizontal, means for feeding the raw mineral to the highest end of said launder, a plurality of 5 adjustable wet sorting apparatus arranged at intervals along and depending from said launder and in communication therewith, adjustable means for supplying liquid under pressure in upward streams to the said sorting apparatus mechanical means for taking up the products discharged by the sorting apparatus farthest away from the aforesaid feeding means and discharging them into the launder between such feeding means and 10 the nearest of the aforesaid sorting apparatus, a launder extension leading with a slight downward slope to the highest end of the aforesaid launder, adjustable means for supplying liquid for a conveying stream to 15 the highest end of said launder extension, an additional adjustable wet sorting apparatus depending from and in communication with said launder extension, adjustable means for supplying liquid under pressure 20 in upward streams to said additional sorting apparatus, mechanical means for taking up the products discharged by the sorting apparatus depending from the launder closest to the aforesaid feeding means and discharging them into the launder extension between the highest end thereof and the additional sorting apparatus, and a crushing mill arranged in said launder extension between the last named sorting apparatus and the high end of the launder, substantially as 25 described.

3. The combination in plant for washing coal and other minerals by means of liquid streams of: a launder having a slight downward slope in relation to the horizontal, means for feeding the raw mineral to the highest end of said launder, a plurality of 30 adjustable upward stream wet sorting apparatus arranged at intervals under said launder and in communication therewith, adjustable controlled means for supplying liquid under pressure to said sorting apparatus, mechanical means for taking up the products discharged at the base of the sorting apparatus depending from the lowest section of the launder and returning them into the portion of the said launder leading to the sorting apparatus depending from the highest section thereof in the direction 35 of the downward slope of such launder, a launder extension leading with a slight downward slope to the highest end of the aforesaid launder, adjustably controlled 40

means for supplying liquid for a conveying stream to the highest end of said launder extension, an additional adjustable upward stream wet sorting apparatus depending from and in communication with said launder extension, adjustably controlled means 45 for supplying liquid under pressure to said additional sorting apparatus, mechanical means for taking up the products discharged by the sorting apparatus depending from the highest section of the launder and conveying them to the portion of the launder extension leading to the aforesaid additional sorting apparatus in the direction of the downward slope of such launder extension, and a crushing mill arranged in said launder extension between the last named sorting apparatus and the adjacent end of the launder, substantially as 50 described.

4. In plant for washing coal and other minerals, the combination of: a launder having a slight downward slope in relation to the horizontal, a feeding hopper for the raw mineral discharging into the highest end of said launder, two upward stream wet sorting apparatus with adjustable sorting chamber and oscillatory discharge flap, arranged at 55 intervals under and in communication with the launder, a bucket elevator having a collecting boot arranged under the base of the sorting apparatus closest to the low end of the launder and a discharge chute adapted to deliver into the portion of said launder leading from the feeding hopper to the other sorting apparatus, a launder extension leading with a slight downward slope to the highest end of the aforesaid launder, adjustably controlled means for supplying liquid for a conveying stream to the highest 60 end of said launder extension, an additional upward stream wet sorting apparatus with adjustable sorting chamber and oscillatory discharge flap, depending from and in communication with said launder extension, adjustably controlled means for supplying liquid under pressure to said additional sorting apparatus, a bucket elevator having a collecting boot arranged under the base of the wet sorting apparatus depending from the aforesaid launder closest to the high end thereof and a discharge chute adapted to deliver into the portion of the launder extension leading to the aforesaid additional sorting apparatus in the direction of the downward slope of such launder extension, and a crushing mill arranged in said launder extension between the last named sorting apparatus and the launder.

In testimony whereof I signed hereunto my name.

ANTOINE FRANCE.
